DEPRESSIBLE TRIGGER ACTUATOR FOR A REVERSIBLE ELECTRIC SWITCH

Harry W. Brown, Mukwonago, Wis., and Raymond C. Ingels, Chicago, Ill., assignors to Cutler-Hammer, Inc., Milwaukee, Wis., a corporation of Delaware

Filed May 15, 1962, Ser. No. 70,144

Term of patent 14 years

(Cl. D26—13)

FIGURE 1 is an isometric view of a depressible trigger actuator for a reversible electric switch, showing our new design;

FIG. 2 is a front elevation view;
FIG. 3 is a side elevation view; and

FIG. 4 is a top plan view thereof.

The dominant features of our design reside in the depressible trigger actuator portions shown in solid lines in the drawings.

We claim:

The ornamental design for a depressible trigger actuator for a reversible electric switch, substantially as shown and described.
